Inventor:

Frank L. Dyer

UNITED STATES PATENT OFFICE.

FRANK L. DYER, OF MONTCLAIR, NEW JERSEY.

SPARK-PLUG.

1,304,462.

Specification of Letters Patent. Patented May 20, 1919.

Application filed January 25, 1918. Serial No. 213,670.

To all whom it may concern:

Be it known that I, FRANK L. DYER, a citizen of the United States, and residing at Montclair, in the county of Essex and State 5 of New Jersey, (post-office address No. 55 Liberty street, New York city,) have invented certain new and useful Improvements in Spark-Plugs, of which the following is a full, clear, and exact description.

10 My invention relates to various new and useful improvements in spark plugs of the general type described in my application for Letters Patent filed April 27, 1917, and numbered serially 164,849. In my said application I show a spark plug in which the central electrode is firmly and securely locked within the porcelain or other refractory insulator, preferably by a process analogous to electric butt-welding. In constructing such plug, I propose taking two lengths of metal of the required diameter, and preferably reduced in cross section at their abutting ends, or what amounts to the same thing, a single length of metal having 20 an intermediate portion cut away to secure the corresponding reduction in cross section, and passing through the metal, or metals, a heating current of low voltage and very high amperage so as to heat the same at the locality of small cross section and make the metal plastic, or even molten, after which pressure is applied lengthwise to cause the plastic or molten metal to form a tight anchoring seal with the porcelain, and also, in 30 the case where two metal lengths are used, to cause the abutting ends thereof to be electrically welded. The advantages of such a spark plug are the ease and economy with which it can be made, and the fact that the 35 central electrode is anchored to the porcelain *in situ*, and each is free to expand or contract under changes in temperature, notwithstanding differences in coefficients of expansion, thus doing away with a potent source 40 of difficulty encountered when the central electrode throughout its length is cemented within the porcelain.

The object of my present invention is to effect a further economy in construction, 45 which I accomplish by making the section of the central electrode, which is exposed to the sparking effects, of nickel, and by

making the rest of the central electrodes of steel or other cheaper metal, the two sections being electrically welded together as I explained in said application.

Another object of my invention is to improve the tightness of the joint between the central electrode and the porcelain, which I do by making the joint of an alloy having 55 nearly the same coefficient of expansion as porcelain. An alloy of nickel and steel, where the percentage of nickel is properly selected, has this property, and therefore when a nickel and steel section are welded 60 together it is possible to so adjust conditions of cross section, current used, etc., as to secure at the weld practically an alloy having the desired coefficient of expansion. Or instead, the entire length comprising the 65 central electrode can be made of the desired alloy—such as nickel-steel, with a reduced intermediate section to be made plastic or molten by the current to effect the required seal. Or instead, between two sections of 70 nickel and steel may be placed an intermediate section of the desired alloy, of smaller cross-section to localize the heat and thus permit the anchoring seal to be formed, and simultaneously weld the nickel and steel 75 sections together.

In order that my invention may be better understood attention is directed to the accompanying drawings forming part of this specification, and in which:

Figure 1 is a longitudinal sectional view of a spark plug porcelain supported in a simple apparatus for the purpose, and with two sections of nickel and steel having correspondingly reduced ends abutted together 80 preparatory to welding;

Fig. 2, a plan view of the clamp for the upper section of the central electrode;

Fig. 3 a cross section on the line 3—3 of Fig. 1;

Fig. 4 a section showing the joint after being formed and constituting a tight seal with the porcelain;

Fig. 5 a longitudinal section on a larger scale showing the two metal sections with 100 differently reduced ends;

Fig. 6 a corresponding view of a slight modification;

Fig. 7 a corresponding view showing the

use of a separate section of the desired alloy where the heat is to be localized, and of which the joint or seal is to be formed;

Fig. 8 a cross section on the line 8—8 of Fig. 7; and

Fig. 9 a longitudinal sectional view showing the central electrode as being formed of a single length of the desired alloy, and having a reduced section where the heating is to be localized.

In the above views, corresponding parts are represented by the same numerals.

The porcelain 1, is shown as supported by the two arms 2, 2, from a base 3 from which 15 extends the section 4 of the central electrode, said section being of nickel or other suitable metal for the purpose. The other section 5, made of steel, is carried by a split clamp 6 (see Fig. 2) to which the desired pressure 20 may be applied.

The heating current is supplied by any suitable transformer 7, being of low voltage—say from 3 to 6 volts and of the desired high amperage. In Fig. 1, the abutting ends 25 of the sections 4 and 5 are shown as correspondingly reduced. When the heating current is applied, the reduced ends become intensely heated to plasticity or even to a molten state, and by applying pressure 30 lengthwise, the metal is squeezed out forming a tight seal as shown in Fig. 4, and simultaneously welding the two sections together. If desired, the heating may be continued until either or both sections 4 and 5 35 is made plastic for a considerable part of its length, so that when longitudinal pressure is applied the metal will be forced radially outward so as to bring a considerable length of the central electrode in intimate contact 40 with the porcelain and thus close the slight air space between the central electrode and the porcelain to permit more effective radiation of heat from the central electrode. This feature is especially important when the central electrode is composed wholly or largely 45 of a nickel steel alloy of nearly the same coefficient of expansion as the porcelain, because in that case the central electrode for its whole length, if necessary, can be 50 squeezed in contact with the porcelain without danger from unequal expansion and contraction.

According to Kent, "The Mechanical Engineers' Pocket-Book", John Wiley & Sons, Inc., New York, 1916, page 499, an alloy of 55 nickel and steel in which the percentage of nickel varies between 28.7% and 34.4% has a coefficient of expansion of from .00001041 to .00000458 for each degree C., and it can be 60 assumed that most spark plug porcelains have a coefficient of expansion in this neighborhood and between these extremes. Therefore, by properly selecting the percentage of nickel in the alloy, a coefficient of expansion 65 can be secured to nearly correspond with

that of the porcelain used. Preferably the coefficient of expansion of the alloy should, if anything, be very slightly less than that of the porcelain, rather than greater, for the reason that the formation of the joint or seal 70 is at a higher temperature than will be encountered in practice, and when the parts cool it is better to have the porcelain shrink tightly on the central electrode than to have the latter shrink away from the porcelain 75 and possibly make the joint leak. The proper proportioning of the two metals constituting the alloy may be affected by varying the cross-sectional areas of the abutting ends as shown in Figs. 5 and 6, and suitably 80 controlling the current and other factors. Or instead, a separate section 8 of the desired alloy may be inserted between the sections 4 and 5, and being suitably reduced in area (for example, as shown in Fig. 8), will 85 affect the localization of the current so as to become plastic or molten, and form the seal when longitudinal pressure is applied, at the same time welding the sections 4 and 5 together. Instead of using two sections 4 and 5 and welding them together, a single length 9 may be used, made of the desired alloy, and reduced at an intermediate part, as shown in Fig. 9, to thus localize the current 90 and permit the metal to be squeezed outward 95 to form the anchoring seal when longitudinal pressure is applied.

Having now described my invention, what I claim as new and desire to secure by Letters Patent, is:

1. In a spark plug, an integral or one-piece porcelain or other refractory insulator therefor and a composite central electrode therein, comprising a nickel section located in the bore of the insulator and which is subjected to the effect of sparking, and a steel section connected thereto and also located in the bore of the insulator, the joint between the sections being located in the bore of the insulator, substantially as set forth.

2. In a spark plug, an integral or one-piece porcelain or other refractory insulator therefor and a composite central electrode therein, comprising a nickel section located in the bore of the insulator and which is to be subjected to the effect of sparking, and a steel section welded thereto and also located in the bore of the insulator, the joint between the sections being located in the bore of the insulator, substantially as set forth.

3. In a spark plug, an integral or one-piece porcelain or other refractory insulator therefor and a composite central electrode therein, comprising a nickel section located in the bore of the insulator and which is to be subjected to the effect of sparking, and a steel section welded thereto and also located in the bore of the insulator,

the joint between the sections being located in the bore of the insulator and being expanded to tightly anchor the composite central electrode in place, substantially as set forth.

4. In a spark plug, a porcelain or other refractory insulator therefor, and a central electrode therein, anchored to the bore thereof by a tight expanded joint of a metal alloy whose coefficient of expansion approximates that of the insulator, substantially as set forth.

5. In a spark plug, a porcelain or other refractory insulator therefor, and a central electrode therein, anchored to the bore thereof by a tight expanded metal joint of a metal alloy whose coefficient of expansion is slightly less than that of the insulator, substantially as set forth.

6. In a spark plug, a porcelain or other refractory insulator therefor, and a central electrode therein, anchored to the bore thereof by a tight expanded joint of a nickel-steel alloy whose coefficient of expansion approximates that of the insulator, substantially as set forth.

7. In a spark plug, a porcelain or other

refractory insulator therefor, and a central electrode therein made of a nickel and a steel section welded together and anchored to the bore of the insulator by an expanded joint of the nickel-steel alloy whose coefficient of expansion approximates that of the insulator, substantially as set forth.

8. In a spark plug, an integral or one-piece porcelain or other refractory insulator therefor and a composite central electrode therein, comprising a nickel section located in the bore of the insulator and which is to be subjected to the effect of 35 sparking, and a steel section welded thereto and also located in the bore of the insulator, the joint between the sections being located in the bore of the insulator and being expanded into intimate contact therewith on both sides of the joint to tightly anchor the composite central electrode in place, substantially as set forth.

This specification signed and witnessed this 24th day of January, 1918.

FRANK L. DYER.
